STEAM IRON

Samuel R. Bricker, Shelby, Ohio, assignor to Westinghouse Electric Corporation, East Pittsburgh, Pa., a corporation of Pennsylvania

Filed Mar. 13, 1962, Ser. No. 179,357

3 Claims. (Cl. 38—77)

This invention relates to electrically heated steam irons, and more particularly to steam irons of the flash type. A primary object is to provide improvements in the valve arrangements and control means therefor.

Steam irons of the flash type are provided with a built-in water tank having a fill opening to permit filling the tank with water for steam pressing operations. The tank in such irons is in communication with a steam-generating chamber disposed in the sole-plate and the flow of the water from the tank is controlled by a suitable water valve. The orifice of such valves is so small that the water flows in a drop-by-drop manner, and, accordingly, it is common practice to refer to these valves as drip valves. It is highly desirable that the fill opening be closed at all times except when the tank is being filled so that during ironing operations there is no danger that the water will be splashed out of the tank. Also it is desired that the water valve between the tank and the steam-generating chamber be closed at all times other than when the iron is being used for steam operation.

In view of the above, it is the primary object of the present invention to provide, in a flash-type steam iron, an improved fill opening closure means, an improved drip valve and an improved interlock between the valve and the fill opening closure means.

Another object is to provide an improved drip valve and fill opening closure arrangement whereby the closure member and the drip valve are controlled by a common control member and in which each is controlled independently of the other and in the proper relation to each other.

In accordance with the invention there is provided a novel and improved flash steam iron in which the drip valve, the fill opening closure member and a single manual actuator are arranged in vertical alignment, with the drip valve and the closure member being biased by a common biasing means in opposite directions toward their respective closed positions and the drip valve and closure member being operated to their open positions by a single actuator moving in opposite respective directions from an intermediate position.

These and other objects are effected by this invention as will be apparent from the following description, taken in connection with the accompanying drawings, forming a part of this specification, in which:

FIG. 1 is a side elevational view, mostly in section, of a portion of an electric iron constructed in accordance with the present invention, showing the manual actuator in the position for "dry" ironing with both the drip valve and the closure member in their respective closed positions;

FIG. 2 is a fragmentary sectional view showing the manual actuator in the "steam" ironing position in which the drip valve is in open position; and

FIG. 3 is a similar view showing the manual actuator in the "fill" position with the closure member in open position.

In accordance with an illustrative embodiment of the invention, there is shown an electric steam iron of the flash type, having a soleplate 11, a water tank or reservoir 12 above the soleplate and a suitable shell or cover 13 cooperating with the soleplate to enclose the tank. The cover 13 is fixed to the soleplate 11 by means of a

2

suitable bracket 14 secured to the soleplate 11 by means of cap screws 16.

The cover 13 is spaced from the top of bracket 14 by a spacer sleeve 17 surrounding a bolt 18 which secures the cover to the top of the bracket 14. A handle unit 19, having a grip portion 20, is secured to cover 13 by screws, one of which is shown at 21.

The handle unit 19 has a front leg 25 provided with a large recess 26, the inside of which is accessible through an access opening normally closed by a top cover 27. The relation between the leg 25 and the improvements provided by this invention will appear from the subsequent description.

The soleplate 11 is provided with a steam generating chamber 10 which is connected by suitable passages 22 to a plurality of steam discharge ports, one of which is shown at 23, directed downwardly through the bottom of the soleplate. A cover plate 24, secured to the upper surface of the soleplate 11 by means of suitable cap screws, one of which is shown at 30, serves as the upper wall of the steam generating chamber and the passages 22. An electrical heating element 26, preferably of the sheathed type, is embedded in the soleplate and serves to heat the latter for "steam" or "dry" pressing of textile material as is well understood in the art. The energization of the heating element and the temperature of the soleplate is controlled in conventional manner.

In the illustrative embodiment of the present invention, the fill opening for the tank 12 and the drip valve between the tank and the steam generating chamber 10 are in vertical alignment, thereby permitting the fill opening closure member and the controls therefor to be conveniently mounted in the forward end of the handle unit 19. Another important feature is the novel arrangement wherein a single biasing spring is arranged between the closure member for the fill opening and the drip valve for simultaneously urging them both at all times toward their closed positions. The linkage for operating the closure member and drip valve is so arranged that movement of the linkage in one direction from an intermediate position opens either the closure member or the drip valve, and movement in the opposite direction opens the other.

These features are illustrated in the drawings where the water tank 12, shown as extending horizontally above the soleplate 11, is provided with a fill tube 28. The fill tube 28 projects upwardly into an undercut annular recess, terminating in a planar surface 29, in the lower side of the front leg 25 of the handle unit 19. The upper edge of the fill tube 28 is sealed to the planar surface 29 by means of a suitable resilient gasket 31, which may be of any suitable heat-resistant material, such as silicon rubber, or the like. The planar surface 29 is provided with a central aperture 32 constituting the fill opening for the water tank 12. The aperture 32 is in direct communication with the flared passage 33, molded into the front of the leg 25. The flared passage 33 constitutes a convenient funnel through which tank 12 may be filled when the iron is in a tilted position with its front end uppermost. The planar surface 29 constitutes a valve seat for a flat resilient disc-like fill valve member 34 for the fill opening 32. The fill valve is opened, when it is desired to fill the water tank, in a manner hereinafter described.

A drip valve 35 through which water is supplied from the water tank 12 to the steam chamber 10 in the soleplate during the "steam" ironing operations comprises a stationary valve body 36 sealed to the bottom of the tank 12 and having a small orifice 38 through which water may flow, drop by drop, when the drip valve 36 is open (FIG. 2). The valve body 36 is beveled at its upper side at 39 to provide a suitable valve seat for a movable valve member 40 at the lower end of a valve stem 41. A small pilot pin 42 is loosely mounted in a bore in the lower end

of the valve stem 41 and serves to keep the small orifice 38 free of foreign particles. The valve stem 41 and its valve 40 are biased toward closed position by means of a suitable spring 43, the lower end of which bears against an annular washer 44 fixed to the valve stem 41. The upper end of the spring 43 engages a washer 46 which bears against the fill valve 34. It will be seen from the construction illustrated and described that the single biasing spring 43 mutually urges both the drip valve 40 and the fill valve 34 in opposite directions toward their respective closed positions.

Associated with the construction described above is an operating linkage, for operating the fill valve 34 and the drip valve 40, that assures that the fill valve and the drip valve can never be opened at the same time. To this end, an operating link 47, connected to a manual actuator member 48 at the top of the front leg 25, has a one-way connection with the valve stem 41 to lift the latter and its drip valve from the seat and is adapted to engage the fill valve 34 to push it down away from its seat. The link 47 has a loop 49, at its lower end, surrounding the valve stem 41 and has a sliding fit therewith when moved downwardly. This loop is positioned between the fill valve 34 and a washer 50 fixed to the valve stem 41.

The upper end of the valve stem 41 slidably engages a hole in the fill valve 34 and a bore 51 in the front leg 25 of the handle unit 19. The bore 51 serves as a guide for the upper end of the valve stem 41. The fill valve 34 is of resilient material and engages the valve stem 41 with a slidable liquid-tight fit. The manual actuator element 48 is pivotally connected at 52 to the upper part of the front leg 25 of the handle unit 19 and has an arm 53 to which the operating link 47 is connected. The arm 53 has a hole 54 through which the upper end of link 47 extends. The connection between the arm 53 and the link 47 is effected through suitable resilient bushings 56 and 57. These bushings, having hemispherical heads, are assembled on the link 47 on opposite sides of the arm 53, between metal washers 58, 59 fixed to the link 47, with their hemispherical heads engaging the hole 54 in the arm 53. The actuator member 48 is provided with a manipulable finger 61 projecting above the top surface of the closure 27. It will be noted that both the closure member 34 and the valve stem 41 are engaging their respective seats when the finger piece 61 is in its intermediate position, corresponding to "DRY" ironing operation.

Referring now to FIG. 2, it will be seen that when the actuator element 48 is pivoted beyond the intermediate position in a counterclockwise direction, the arm 53 lifts the operating link 47 so that the looped end 49 engages the washer 50 and lifts the drip valve 40 from its seat. This corresponds to the "STEAM" ironing operation, as indicated by the position of the finger piece 61 since the water can flow through the drip valve 35, as indicated by the arrows 62. It will be seen that when the link 47 lifts valve stem 41 the fill valve 34 is not affected since the biasing spring 43 is merely further compressed and increases its closing force on the fill valve.

Referring now to FIG. 3, it will be noted that the actuating member 48 has been moved in the clockwise direction past the intermediate position to the position designated as "FILL" by the finger piece 61. In this position the arm 53 pushes the link 47 downwardly so that the loop 49 engages the closure member 34, pushing it from its seat and further compressing the spring 43 and thus urging the drip valve 40 tighter against its seat 39. When the iron is placed in a tilted position, with its front end uppermost, the tank 12 may be filled by pouring water into the flared opening 33, from whence it will flow, as indicated by the arrows 63, into the tank or reservoir 12.

From the foregoing description it will be readily apparent that the present invention provides an improved and novel construction in steam irons in which the fill valve and the drip valve are vertically aligned and may be operated by a single actuating member which opens the fill

valve without disturbing the drip valve when moved in one direction and permits the fill valve to move to closed position, and opens the drip valve when moved in the opposite direction beyond the point where said closure member has returned to closed position. This construction also reduces the number of parts required since, among other things, a single biasing spring is used for both valves.

In the illustrated embodiment of the invention, it is apparent that the actuator 48 will normally rest in the "DRY" position with both the drip valve and the closure member in their respective closed positions. The actuator 48 must be held by the finger piece 61 in either the "STEAM" position or the "FILL" position, and this may be accomplished by friction between a protuberance 65 at the front of the actuator 48 and the arcuate surface 66 of the front wall of the recess 26. However, the means for reciprocating the actuating link 47 forms no part of the present invention, and it will be readily apparent that any other suitable means may be provided for positioning and holding the link 47.

While the invention has been shown in but one form, it will be obvious to those skilled in the art that it is not so limited, but is susceptible of various changes and modifications without departing from the spirit thereof.

What is claimed is:

1. An electric steam iron having a soleplate provided with a steam generating chamber and apertures connected to said chamber for discharging steam from said chamber, a water tank disposed above said soleplate, a fill opening at the top of said tank, a fill valve for said fill opening, a drip valve in the bottom of said tank connecting said tank to said steam generating chamber and being vertically aligned with said fill opening, said fill valve and said drip valve having seats facing each other, said drip valve having an operating stem extending upwardly through said fill opening, said fill valve having an opening therein adapted to slidably receive said valve stem, resilient means operably associated between said fill valve and said valve stem adapted to resiliently bias said fill valve and said drip valve in opposite directions toward their respective seats, and an actuating element adapted to engage said fill valve to push the latter from its closed position against said resilient means when moved in one direction and being operably associated with said drip valve to move the latter to open position when said actuating element is moved in the opposite direction beyond the point where said fill valve has returned to closed position.
2. An electric steam iron having a soleplate provided with a steam generating chamber and apertures connected to said chamber for discharging steam from said chamber, a water tank disposed above said soleplate, said water tank having an upstanding cylindrical fill tube, a handle unit anchored to said soleplate above said tank, said handle unit having a downwardly facing surface in sealing engagement with said fill tube and having an opening in said surface constituting a fill opening for said water tank, a drip valve in the bottom of said tank vertically aligned below said fill opening, said drip valve having an operating stem secured thereto and extending vertically upward through said fill opening, a fill valve for said fill opening adapted to engage said downwardly facing surface on said handle unit and slidably engaging said valve stem,

resilient means operably associated between said fill valve and said drip valve stem to thereby resiliently urge both said fill valve and said drip valve stem to their respective closed positions, and
 an actuating element adapted to move in one direction 5
 to engage said fill valve to push it to open position against the force of said resilient means, said actuating element having
 an operating connection with said valve stem to move 10
 said drip valve to open position after said actuating element is moved in the opposite direction beyond the point where said fill valve has returned to closed position.
 3. An electric steam iron having
 a soleplate provided with 15
 a steam generating chamber and
 apertures connected to said chamber for discharging steam from said chamber,
 a water tank disposed above said soleplate,
 means including 20
 a drip valve for controlling the flow of water from said tank to said chamber,
 a fill tube attached to the top of said tank,
 a handle unit anchored to said soleplate above said tank and having 25
 a downwardly facing surface engaging the upper end of said fill tube, said surface having
 an aperture therein constituting a fill opening for said water tank, said drip valve being located in the bottom of said tank in vertical alignment with said fill opening, said drip valve having 30

an operating stem integral therewith extending upwardly through said opening,
 a disc-like fill valve slidably engaging said valve stem and adapted to engage the underside of the surface on said handle unit to close said fill opening,
 a spring surrounding said valve stem, said spring having one end operably connected to said valve stem and the opposite end acting against said fill valve, whereby said spring resiliently urges said drip valve and said fill valve toward their respective closed positions, and
 an actuating element adapted to engage the side of said fill valve opposite said spring to push said fill valve away from said surface on said handle unit when moved in one direction, said actuating element having a one-way operating connection with said valve stem and adapted to move said drip valve to its open position when moved in the opposite direction beyond the point at which said fill valve is returned to its closed position.
